UNITED STATES PATENT OFFICE.

WILLIAM L. HAMILTON, OF CHICAGO, ILLINOIS.

REGISTER-HOOK.

No. 873,043.

Specification of Letters Patent.

Patented Dec. 10, 1907.

Application filed November 24, 1906. Serial No. 344,900.

To all whom it may concern:

Be it known that I, WILLIAM L. HAMILTON, a citizen of the United States, residing at 5702 Union avenue, in the city of Chicago, 5 county of Cook, and State of Illinois, have invented a new and useful Improvement in Register-Hooks, of which the following is a specification.

My improvement relates to that class of 10 tools known as "hooks and base blocks" used by printers to securely support printing plates in position in a "form" made up for printing purposes.

The object of my invention is to provide a 15 "hook" of simple construction; of easier and more extended adjustment; adapted for holding the greatest variety of printing plates; that can be combined with the base blocks of any size on which the printing 20 plates are supported and in which the clutch screw can be operated with a lever pin and a "ratchet"—(a tool in common use by pressmen.)

The manner in which I accomplish my object is described in the following specification and illustrated in the accompanying drawings in which:

Figure 1—is a plan view showing six of 30 my hooks in position holding a printing plate supported on ordinary printers blocks. Fig. 2—is an end elevation showing the form of the body of my hook, end of screw and clutch and lever pin. Fig. 3—is a plan view showing the top of the clutch, part of the 35 screw and the center bearing groove therein; part of the main body being broken away. Fig. 4—is a cross sectional view on line 4—4, Fig. 3—showing the curved side in the body adapted to project into the central bearing 40 groove of the screw. Fig. 5—is a longitudinal central sectional view on the line 5—5, Fig. 3. Fig. 6—is a perspective view of the clutch removed from the body part of the hook. Fig. 7—is a plan view of my com- 45 bined hook and base block; this view is 50 illustrative of the varied surface sizes adapt- 55 ed for the various sized plates that may be 60 used in one "form". Fig. 8—is an end ele- 65 vation of a part of one of the base blocks. Fig. 9—is a cross section on the line 9—9, 70 Fig. 7, showing the key-way in the base block and the locking key in the key-way to 75 hold the screw in position. Fig. 10—is a 80 perspective view of the key and screw. Fig. 11—is a view of the locking key.

In the drawings A indicates the body of the hook which may be of any suitable material and size for the use intended. Through the longitudinal center of this body is a channel A¹ having a same circular bottom,— 60 A² and open top A³. In the upper part of this channel both sides are formed into corresponding longitudinal guide ways A⁴ and A⁵. This channel and these guide ways extend the full length of the body A. 65 Extending across the center of the length of the channel A¹ and projecting above the circular bottom A² is a curved rib A⁶ shown in Figs. 4 and 5. This rib may be an integral part of the body A, or be affixed 70 therein. One end of the body A is cut down and forms a ledge A⁷. Within the channel A¹ and extending the full length thereof is a screw shaft B. The surface B¹ of this shaft is threaded from end to end. 75 In the center of the length of this shaft is an annular groove B² adapted to fit the projecting rib A⁶ in the body A, as shown in Figs. 4 and 5. In the threaded surface of the shaft are longitudinal parallel grooves 80 B³ shown in the end view, Figs. 3 and 10. The threaded surface of this shaft is of a diameter adapted to permit said shaft to be inserted endwise into the channel A¹ over the rib A⁶, and to be lowered into 85 place with said rib in the groove B² in which position it is free to be revolved, but cannot be moved longitudinally. A clutch C, constructed with external bearing surfaces C¹ and C² corresponding with and 90 adapted to fit the guide ways A⁴ and A⁵ in the body A, is adapted to be inserted in said body and to slide freely in said bearing surfaces. The underside C³ of this clutch is curved and threaded as shown in 95 Figs. 5 and 6 to correspond with the threaded surface of the shaft B and is thereby adapted to fit into the thread on said shaft when said clutch is inserted in said body and to be moved therein by the rotation of said shaft. 100 Forming part of said clutch and extending transversely to the bearing surfaces C¹ and C² is a jaw C⁴. This jaw is located at one end of the clutch and has an inward beveled face C⁵ shown in Figs. 5 and 6. 105 The top surface C⁶ of the clutch is adapted to correspond with the height of the top A⁸ of the body A and form with it a level surface. The outer end C⁷ is narrowed as shown in Figs. 2 and 3.

When constructed as described and illustrated in the drawings, the "hook" is put together and used as follows: The shaft is inserted endwise into the body A and placed over the side in the bottom thereof. One end of the clutch C is then inserted in the bearing surfaces in the body and in contact with the threaded surface of the shaft, which is then revolved in the right direction and the clutch is thereby drawn into the body as shown in Fig. 3. Several of these "hooks" are placed in position in the form in contact with the ordinary supporting blocks used for printing plates, indicated by A⁹, Fig. 1 (and backed up by other blocks inserted between the hooks and "chase" not shown) so that the edges of the printing plate will be over the top C⁶ of the clutch. The shaft B is then rotated and the clutch is moved rapidly either way in the main body by a hand rack moved along the ledge A⁷ the teeth of said rack entering the grooves B³ and thereby rotating the shaft, and by lever pin E which is adapted to be inserted in the grooves B³, as shown in Fig. 2. The beveled face C⁵ of the jaw C⁴ is thereby firmly pressed against the edge of the printing plate D, as shown in Figs. 1 and 7.

The combination of hook and base block is accomplished by increasing the surface size of the body A, and extending the channels A¹ and guide ways A⁴ and A⁵ the full length and width of the body A, increasing the number of channels in proportion to the size of the body, from side to side at right angles as shown in Fig. 7. In these hook and base blocks there are no ribs A⁶ across the bottom of the channels, in which the screw shaft B can be moved from end to end. For the purpose of securing the screw in the position required in the channel, a key F, Fig. 11, is inserted in key-ways F¹, constructed at certain distances in the block through the guide-ways and sides of the channels to a depth adapted to allow the bottom ends of the key to engage the horizontal center of the grooved part B² of the screw B as shown in Figs. 8 and 9 in which position the screw B is securely held in position and the clutch C is free to be moved over the top of the key F, as shown in Fig. 9 as the screw is rotated. The screw, when in position in the channel, rests on the bottom as shown in Figs. 8 and 9, and together with the clutch can be moved to any one of the key-ways and be secured in position close to the edge of the plate D by the insertion of the key—a partial rotation of the screw by the lever E locking the clutch and plate. The ledge A⁷ is made in the ends of the main body A to permit of the operation of the screw by a hand rack moved along said ledge, and by the lever pin E for the final adjustment of the clutch and when the position of the plate D and the clutch C requires the

jaw C⁴ to be at the extreme end of the body A, as shown in Fig. 3.

What I claim and desire to secure by Letters Patent is:

1. In a device of the kind described the rectangular body, said body having a transverse ledge at one end, a cylindrical channel extending longitudinally therethrough and longitudinal parallel guideways forming the open top of said channel; the shaft insertible in said channel, the surface of said shaft being threaded the full length and channeled longitudinally by a series of parallel channels extending the full length of said shaft, and having a central annular channel; the projection in said body adapted to enter said annular channel in said shaft; the clutch slidably supported in said guideways, said clutch having an arched and threaded under surface adapted to mesh into the threaded surface of said shaft, and thereby adapted to be moved from end to end of said body by the rotation of said shaft.

2. In a device of the kind described, the combination with the main body, said body having a transverse ledge at one end, a cylindrical channel extending longitudinally therethrough and longitudinal parallel guideways; of a shaft insertible in said channel, the surface of said shaft being threaded the full length, channeled from end to end with a series of parallel channels and having an annular channel in the central part adapted to admit a projection in said cylindrical channel adapted to prevent a lateral movement of said shaft in said body; and a clutch insertible in said guideways adapted to be engaged and moved therein by the rotation of said shaft.

3. In a device of the kind described, the combination with the main body having a transverse ledge at one end, a cylindrical channel extending therethrough and parallel guideways, and a shaft insertible in said channel, the surface of said shaft being threaded and channeled longitudinally with a plurality of parallel channels and having an annular channel; of a projection in said cylindrical channel adapted to enter said annular channel in said shaft and to thereby prevent its lateral movement in said main body, and a clutch slidably supported in said guideways, said clutch being adapted to engage said shaft and be moved by its rotation in said body.

4. In a device of the kind described, the combination with the main body, the shaft revolvably supported therein, the surface of said shaft being threaded and channeled the full length, and means in said body adapted to prevent the lateral movement of said shaft in said body; of a clutch slidably supported in said body, said clutch having an arched under surface said surface being threaded and adapted to mesh into the threaded sur-

face of said shaft, said clutch being thereby adapted to be moved from end to end of said body by the rotation of said screw.

5. A register hook having a rectangular body, a cylindrical channel extending through said body, the open parallel sides of said channel forming guideways adapted to hold a clutch; a surface threaded shaft insertible and revoluble in said channel, said 10 shaft having surface parallel channels adapted to admit the end of an operating lever and to be thereby rotated in said body, and an annular groove in said shaft adapted to admit means in said body whereby the lateral

position of said shaft in said body is fixed; a 15 clutch slidably supported in said guideways in which it is free to be moved from end to end of said body, said clutch having an arched under surface, said surface being threaded and thereby adapted to mesh into 20 the threaded surface of said shaft and to be moved in said guideways by the rotation of said shaft.

WILLIAM L. HAMILTON.
